UNITED STATES PATENT OFFICE

115,792

DESIGN FOR A BOTTLE

Frederick R. Hoch, Norton, Mass., assignor to
T. J. Holmes Co., Inc., Chartley, Mass., a corporation of Massachusetts

Application November 15, 1938, Serial No. 81,091

Term of patent 3½ years

To all whom it may concern:

Be it known that I, Frederick R. Hoch, a citizen of the United States, residing in Norton, in the county of Bristol and State of Massachusetts, have invented a new, original, and ornamental Design for a Bottle, of which the following is a specification, reference being had to the accompanying drawing, forming a part thereof.

In the drawing:

Fig. 1 represents a plan view of a bottle showing my new design;

Fig. 2 is a front elevation of the bottle shown in Fig. 1;

Fig. 3 is a side elevation taken from the left hand side of the bottle shown in Figs. 1 and 2, and

Fig. 4 is a side elevation taken from the right hand side of the bottle shown in Figs. 1 and 2.

I claim:

The ornamental design for a bottle, as shown.

FREDERICK R. HOCH.
